H. G. O'NEILL.

CONTROLLING MEANS FOR ENGINE STARTERS.

APPLICATION FILED MAR. 1, 1915.

1,314,894.

Patented Sept. 2, 1919.

UNITED STATES PATENT OFFICE.

HENRY GIBSON O'NEILL, OF NEW YORK, N. Y., ASSIGNOR TO CONRAD HUBERT, OF HEWLETT, NEW YORK.

CONTROLLING MEANS FOR ENGINE-STARTERS.

1,314,894.

Specification of Letters Patent.

Patented Sept. 2, 1919.

Application filed March 1, 1915. Serial No. 11,140.

To all whom it may concern:

Be it known that I, HENRY GIBSON O'NEILL, a citizen of the United States, residing at the borough of Manhattan, city of New York, 5 in the county of New York and State of New York, have invented certain new and useful Improvements in Controlling Means for Engine-Starters, of which the following is a specification, reference being had therein 10 to the accompanying drawings, forming part thereof.

My invention relates to engine starting apparatus of the type which is adapted to crank an internal combustion engine, particularly of a motor car, and of the kind in which means are provided for assuring that the ignition spark of the engine shall be retarded during the cranking operation. My invention relates more particularly to electrically operated engine starting apparatus 20 and is equally applicable to the single unit type in which a combined dynamo and motor commonly known in the art as a dynamo-motor is employed as a dynamo operated by the engine for generating electrical energy which is stored and utilized in the dynamo-motor operated as a motor for cranking the engine, and to the two unit type in which a dynamo is employed for 25 generating electrical energy which is stored and utilized in a separate electric motor for cranking the engine. My invention relates more particularly to means for controlling the operation of the engine starting and 30 energy generating apparatus.

The principal objects of my invention are inexpensiveness of manufacture, simplicity of construction, dependability in operation, and convenience of use. Other objects and 40 advantages of my invention will hereinafter appear.

My invention includes, in combination, connections between the manually operable means for operating the spark advancing 45 and retarding device and the engine-cranking device for setting the latter in operation to crank the engine when the said manually operable means is operated to move the spark advancing and retarding device to a 50 retarded spark position while maintaining the integrity of the ignition circuit in any position of said device between the engine-starting position and the position of most

advanced spark under self actuation of the engine.

I shall now describe the two engine starting equipments embodying my invention illustrated in the accompanying drawings and shall thereafter point out my invention in claims.

Figure 1 is an elevation partly in section and with parts omitted of the circuit controlling means.

Fig. 2 is a vertical section on planes indicated by the line 2-2 of Fig. 1 as viewed from right.

Fig. 3 is a view from the rear of the steering wheel of a motor car with parts broken away and shows in longitudinal section the automatic controlling device there appearing.

Fig. 4 is a front elevation of the same on a reduced scale.

Fig. 5 is a transverse section of the spark lever and parts of the steering wheel on a 75 plane indicated by the diagonal line 5-5 of Fig. 3 as viewed from below and shows the attachment of said controlling device to the steering post.

Fig. 6 is a diagram of the electric circuits, 80 engine starting apparatus and controlling means, illustrating the application of my invention to the dynamo-motor or single unit type of engine starting apparatus.

Fig. 7 is a similar diagram illustrating 85 the application of my invention to the two unit or separate dynamo and motor type of engine starting apparatus.

In the electrical equipment embodying my invention illustrated in the accompanying drawings, a bent controller-operating lever 1 is shown as clamped in fixed position upon the operating rod 2 of the usual spark advancing and retarding device. This operating rod 2 as illustrated in the drawings lies 95 alongside of the steering rod or steering shaft 3 and the upper portions of the operating rod 2 and steering rod 3 are inclosed and supported by the steering column or steering post 3a. The spark controlling or 100 operating rod 2 is provided at its upper end with the usual manually actuatable spark lever 4 which projects just beneath the rim of the steering wheel 5, (Figs. 3, 4 and 5) and at its lower end the operating rod 2 105 has the usual connection by means of a lever

arm 6 and operating rod 7 with the usual timing device or distributor 8 of the ignition apparatus which may be of the usual or of any suitable construction.

5 Referring more particularly to Figs. 1 to 6 inclusive, the controller-operating lever 1 operates a circuit controller in control of both the engine starting and the energy generating operations of a dynamo electric machine which is a combined dynamo and motor or dynamo-motor having a rotative armature 9 and stationary field 10 shown as compound wound as appears in Fig. 6. The bent controller-operating lever 1 is arranged to enter 15 gage at its free end a pivoted lever 11 of the circuit controller, such engagement taking place at a certain predetermined position of retarded spark, this being the position of the parts illustrated in the drawings. The 20 circuit controller lever 11 operates a sliding rod 12 which passes through and is guided by a casing 13 and which is moved to its uppermost position by a coiled thrust spring 14. The slide rod 12 carries upper and 25 lower contact bars 15 and 16 of which the lower bar 16 is shown as fixed on the rod 12 but the upper bar 15 is pressed upwardly toward an abutment pin 17 by a coiled thrust spring 18 surrounding the rod 12 above an 30 abutment collar 19. When the slide rod 12 is elevated by the spring 14 as shown in the drawings, the upper contact bar 15 will make an electrical connection between a pair of stationary contact terminals 20 and 21 mounted 35 upon but insulated from the casing 13 and the lower contact bar will make a like connection between another pair of similarly mounted stationary contact terminals 22 and 23, it being understood that the contact 40 bars 15 and 16 are insulated from the slide rod 12 as indicated in Figs. 1, 2 and 6. The lower contact bar 16 is also co-operative with a pair of motor circuit controlling contact members 24 and 25 shown as supported upon 45 and insulated from the bottom of the casing 13 and projecting upward in the path of the lower contact bar 16.

In the diagrammatic representation in Fig. 50 the electric circuits are shown as of the single wire or grounded type, the frame of the motor car serving as a common return conductor as is well understood. A storage battery 26 is employed and the generating circuit or circuit from the dynamo-motor 55 9-10 operated as a dynamo to the storage battery 26 includes a conductor 27, upper left contact member 20, upper contact bar 15, upper right contact member 21, a conductor 28, a current regulating device 29, 60 a conductor 30, the lower right contact member 23, a conductor 31, the bottom right contact member 25 and a conductor 32 to the battery 26. The engine cranking circuit or electric circuit from the storage battery 26 to 65 the dynamo-motor 9-10 operated as an en-

gine starting motor for cranking the engine is through the battery line conductor 32, the bottom right contact member 25, the lower contact bar 16, the bottom left contact member 24 and a conductor 33, to the dynamo-motor 9-10. A lighting circuit 34 is shown as connected in multiple with the battery 26 and dynamo-motor generating circuit such connection being shown as made to the conductor 30. The current regulator 29 is connected in the generating circuit in the usual way and may be of any suitable construction, this current regulator being illustrated diagrammatically in Fig. 6 and it appears in elevation at the left in Fig. 1. As is well understood in the art, the current regulator 29 controls the charging of the storage battery 26 and also prevents discharge of the battery through the generating circuit, such as in the present instance would otherwise occur should the engine be stopped with the spark advanced and hence with the circuit closer in position to close the generating circuit. An electric meter 35 is shown as connected to the lower left contact member 22 90 so as to be included through the lower contact bar 16 in the combined generating and battery circuit in multiple relation with the lighting circuit 34.

When the spark lever 4 is retarded or 95 moved in a clockwise direction beyond the position shown in the drawings (see Fig. 3 particularly) the bent controller-operating lever arm 1 will come in contact with and depress the circuit controller lever 11 and the generating circuit will be opened by the upper contact bar 15 moving away from the upper contact members 20 and 21, also incidentally the circuit of the meter 35 will be similarly opened by the lower contact bar 16 100 moving away from the contact members 22 and 23. Further spark-retarding movement of the spark lever 4 will bring the lower contact bar 16 into contact with the two bottom contact members 24 and 25, this latter contact relation being established at the usual or normal position of maximum spark retardation, and without any interference with the functions of the spark advancing and retarding device of the engine, it being noted 115 in this connection that the usual ignition circuit is not affected and remains in operating or sparking condition. As soon as electrical connection is made from the lower bottom right contact member 25 through the 120 lower contact bar 16 to the bottom left contact member 24, the dynamo-motor 9-10 will be energized as a motor, the result being that the engine is started by the dynamo-motor operated as a motor to crank the engine. 125

For convenience of operation and also to obviate the possibility of accidental unnecessary drains upon the battery 26 and furthermore to prevent the spark lever 4 from ever 130

being moved through inadvertence to the maximum retard position corresponding to the engine starting operation, an automatically acting device is provided for moving 5 the spark lever 4 away from the position of combined maximum spark retardation and engine-starting operation of the dynamo-motor 9-10. This automatically acting restoring device is shown in the drawings as a 10 spring actuated device mounted on the steering column 3^a just beneath the steering wheel 5 in the path of the spark lever 4 as it is moved toward the position of maximum spark retardation and engine-starting operation. A tubular socket 36 is clamped to the 15 upper end of the steering column 3^a by a supporting clamp 37 (Figs. 3, 4 and 5). The socket 36 contains a coiled thrust spring 38 which pushes outwardly a piston or plunger 39 whose outward movement is limited 20 by a pin 40 fixed in the tube 36 and passing through a slot in the plunger 39 as clearly appears in Fig. 3. The outer free end of the plunger 39 is positioned in the path of 25 the spark lever 4 at the proper place so that the engine-starting circuit will not be completed until after the plunger 39 has been pushed in by the spark lever 4 against the tension of the plunger spring 38. In effecting an 30 engine starting operation all that the driver has to do is to move the spark lever 4 toward the spark retarding position as far as possible after this lever comes in contact with the plunger 39, compressing the plunger 35 spring 38, and then the driver should hold the spark lever 4 in this combined spark retarding and engine starting position until the engine starts after which he simply removes his hand from the spark lever and 40 the motor-controlling circuit will be automatically opened by reason of the pushing forward of the spark lever 4 by the plunger 39 under the actuation of the spring 38.

It will now be understood that by the same 45 movement and by the same means by which the ignition spark is retarded an engine starting operation is effected with maximum retardation of the spark thereby rendering a back-fire during the starting operation an 50 impossibility and also requiring no additional movements on the part of the driver other than the spark controlling operation which must be performed anyway to retard the spark previously to starting the engine. 55 It is also to be noted as a feature of importance that the usual or normal functions of the spark advancing and retarding device of the engine are in no manner interfered with. A new function is given to the spark advancing and retarding device, but its usual 60 spark time controlling function continues to be exercised in the usual way the same as if the engine-starting apparatus were not present. After the engine has started the spark lever

4, which now has a super-added function by 65 reason of which it has become also an engine-starting lever, may be moved out of contact with the spring-pressed plunger 39 to advance the spark in the usual way as may be desired. 70

When the spark lever 4 in its spark-advancing movement reaches the position shown in the drawings, the closing of the generating circuit through the upper contact bar 15 will take place and the dynamo-motor 9-10 will be operated as a generator 75 as hereinbefore explained. Further movement of the spark lever 4 in this counter-clockwise spark-advancing direction will lift the free end of the curved controller-operating lever 1 free from the circuit controller lever 11 as will be readily understood from the drawings, particularly Fig. 2, and the operation of the dynamo-motor 9-10 as a generator will continue undisturbed. It 80 will now be understood that if at any time the spark be retarded a certain predetermined amount corresponding to a movement of the spark lever 4 in a clockwise direction beyond the position of this lever shown in 85 the drawings, the generating circuit will be opened by reason of the curved controller-operating lever 1 coming into contact with and depressing the circuit controller lever 11 causing the upper contact bar 15 to move 90 away from the upper contact members 20 and 21. This feature of the invention is of great advantage in relieving the engine from 95 the extra load of generating current during hill climbing, and also it is to be noted requires no extra movements of the driver other than the usual one of retarding the spark as is commonly done in climbing a 100 hill or under similar circumstances.

In the construction shown in the drawings 105 (Fig. 6) a spur pinion 41 is fixed upon the armature shaft 42 of the dynamo-motor 9-10 and meshes with a spur gear 43 which is fixed on a shaft 44 which may be the engine shaft or an extension thereof coupled 110 thereto. In the construction shown in the drawings the speed reduction effected from the armature shaft 42 to the engine shaft 49 is at the rate of about one rotation of the engine shaft 44 to three rotations of the 115 armature shaft 42, in the engine starting operation of the dynamo-motor in cranking the engine.

In the energy generating operation of the dynamo-motor the dynamo-motor is driven 120 from the engine through the gear 43 and pinion 41 which now act as multiplying gearing so that the dynamo-motor will be operated as a dynamo at an increased speed of about three rotations of the armature 125 shaft 42 to one rotation of the engine shaft 44. However, if desired and as is well understood in the art, differential gearing and

clutches may be employed between the armature shaft 42 and engine shaft 44 so that the engine starting operation will be effected at one ratio of speed reduction from the 5 dynamo-motor operated as a motor for cranking the engine and the energy generating operation will be effected at a different ratio of speed from the engine to the dynamo-motor operated as a dynamo.

10 In the engine starting equipment diagrammatically illustrated in Fig. 7 there is no modification or alteration required of the controlling means of my invention, and corresponding parts are accordingly designated 15 by the same reference numerals employed in Figs. 1 to 6 inclusive, but in Fig. 7 my invention is shown as applied to the control of a two unit engine starting apparatus having an engine starting electric motor 45 separate 20 from and independent of an energy generating dynamo 46. A conductor 47 forms part of the dynamo circuit and connects the dynamo 46 to the upper left contact member 20 of the circuit controller, and a conductor 25 48 forms part of the motor circuit and connects the motor 45 with the lower left contact member 24 of the circuit controller. The generator circuit including the conductor 47 is controlled by the upper contact bar 30 15 and the engine cranking motor circuit including the conductor 48 is controlled by the lower contact bar 16 in the same way as the generator circuit including the conductor 27 and the motor circuit including the 35 conductor 33 were controlled in the first described construction.

The dynamo 46 is shown as arranged to be operated from the engine shaft 49 by means of suitable multiplying gears 50 and 51. 40 The motor 45 is connected to the engine shaft 49 to effect an engine starting operation by cranking the engine at a suitably reduced rate of speed by means of a starter pinion 52 and gear 53, the latter being 45 rotatively connected to the engine shaft 49 by a one-way clutch 54 so that when the engine starts it can freely speed ahead of the motor as is well understood.

In other respects than as particularly described the construction and operation of the 50 engine starting equipment illustrated in Fig. 7 are substantially the same as that herein-

before described and illustrated in Figs. 1 to 6 inclusive.

It is obvious that various modifications 55 may be made in the constructions shown in the drawings and above particularly described within the principle and scope of my invention.

I claim:

1. An engine-starting apparatus of the type which is adapted to crank an internal combustion engine and of the kind in which means are provided for assuring that the ignition spark of the engine shall be retarded during the cranking operation, characterized by having, in combination, a spark advancing and retarding device for the engine, manually operable means for operating such device including means for maintaining 65 the integrity of the ignition circuit in any position of said device between the engine-starting position and the position of most advanced spark under self-actuation of the engine, an engine-cranking device, and connections between said manually operable operating means and the engine-cranking device for setting the latter in operation to crank the engine when the said manually operable means is operated to move the 70 spark advancing and retarding device to a retarded spark position.

2. The invention claimed in claim 1 in which the engine-cranking device is an electric motor having a cranking circuit which 85 is closed or opened by the manually operable means for operating the spark advancing and retarding device of the engine.

3. The invention claimed in claim 1 in which the engine-cranking device is a dynamo 90 electric machine having a generating circuit and a cranking circuit, and in which the manually operable means for operating the spark advancing and retarding device opens the generating circuit and closes the 95 cranking circuit or opens the cranking circuit and closes the generating circuit.

In testimony whereof I have affixed my signature in presence of two witnesses.

HENRY GIBSON O'NEILL.
